UNITED STATES PATENT OFFICE.

MICKAEL LEMP, WILLIAM F. ALBRECHT, AND JOSEPH SHEBOL, OF SYRACUSE, NEW YORK, ASSIGNORS TO NOTOWL MANUFACTURING COMPANY, OF SYRACUSE, NEW YORK, A CORPORATION OF NEW YORK.

LAVATORY-FIXTURE.

1,224,306.

Specification of Letters Patent.

Patented May 1, 1917.

Application filed July 15, 1915. Serial No. 40,037.

To all whom it may concern:

Be it known that we, MICKAEL LEMP, WILLIAM F. ALBRECHT, and JOSEPH SHEBOL, citizens of the United States of America, and residents of Syracuse, in the county of Onondaga, in the State of New York, have invented new and useful Improvements in Lavatory-Fixtures, of which the following, taken in connection with the accompanying 10 drawings, is a full, clear, and exact description.

This invention relates to certain improvements in lavatory fixtures adapted to be used in public or private lavatories for drying the hands and face by means of a current of heated air after washing or bathing.

The main object is to place under the control of the user simple, economical and efficient means for projecting a heated current 20 of air in different directions or at different elevations to be used for drying the moistened face and hands, and thereby avoiding the dangers from infection and other unsanitary conditions incidental to the use of 25 towels and similar drying devices.

Another object is to assemble the blower, motor and heater in compact co-axial relation within a suitable housing in such manner that the air delivery nozzle may be adjusted about the axis for directing the projected air to different heights or angles as 30 may be required for drying the hands or face of the same or different users.

A further object is to provide means, 35 operable at will, for holding and releasing the nozzle in and from its adjusted position, and to weight such nozzle in such manner that it will automatically return to a predetermined normal position.

A still further object is to connect the 40 electric motor and the electric heater to a single switch and to establish suitable connections between the movable member of the switch and nozzle-holding means where- 45 by the switch will be closed and opened simultaneously with the operation of the holding means to and from its holding position.

Other objects and uses relating to specific 50 parts of the device will be brought out in the following description.

In the drawings—

Figure 1 is a front elevation of a lavatory fixture embodying the features of our invention.

55

Fig. 2 is a side elevation partly in section of the same device.

Fig. 3 is an enlarged vertical sectional view of the upper portion of the device, taken on line 3-3, Fig. 1.

60

Fig. 4 is an enlarged horizontal sectional view taken on line 4-4, Fig. 2, except that the electric motor is shown in elevation.

Fig. 5 is an enlarged transverse vertical sectional view, taken in the plane of line 5-5, Fig. 4.

As illustrated, this device comprises an upright standard —1— having a suitable base —2— adapted to be secured by bolts or other fastening devices to the floor of 70 the room in which the apparatus is installed, the standard and base being preferably made of cast metal and hollow to receive portions of the operating mechanism hereinafter described.

75

Secured to the upper end of the standard is an upright housing —3— also of cast metal and hollow for receiving a suitable air blower —4—, an electric motor —5— and an electric heater —6—, together with 80 an electric switch —7— and such other devices as it may be desired to conceal and protect within the housing.

The casing —3— is preferably made in sections for convenience of assembling, adjustment and repairs of the various parts inclosed therein, and comprises a main body —8—, a hood —9— and a switch-supporting section —10—, together with a mirror and display frame —11—.

85

The main body —8— is secured at its lower end by screws or bolts —12— directly to the flanged upper end of the standard —1— and extends upwardly around the front side of and some distance above the 95 blower and its motor to receive and support the mirror and display frame —11— which is substantially rectangular and disposed flatwise vertically so as to face the front for receiving and supporting a mirror —13— 100 and a display plate —14— bearing instructions for the use of the machine and any

other matter which it may be desired to place thereon, said frame being secured at its lower end to the upper end of the body —8— by screws or bolts —15—.

5 The hood —9— is secured by suitable fastening means as bolts —16— to the rear face of the upright portion of the main body —8— and is provided in its rear side with an air inlet —17— which may open into the 10 room in which the device is located or may be connected to a pipe —18— shown by dotted lines and leading to the exterior of the building or to any source of pure air supply.

15 The portions of the housing surrounding the blower and motor are substantially semi-cylindrical and formed with spherical ends, as shown more clearly in Figs. 1, 2 and 4, so as to conform as nearly as possible to the 20 casings for the blower and motor, leaving just sufficient clearance for the free adjustment of those parts.

The blower comprises a rotary impeller —19— and a circular casing —20— therefore having an axially extending hollow hub —21— and a tangentially extending delivery nozzle —22— projecting forwardly to the exterior of the housing through a vertical circumferentially elongated slot or opening —23— centrally in the front wall of the main body —8— of said housing so as to allow the delivery nozzle to be adjusted vertically and rotarily about the axis of the impeller to different positions for 35 directing the projected current of air to different angles or heights as may be required by the user in drying the hands or face.

The electric motor —5— is co-axial with the blower —4—, the case of the motor and that of the blower being secured together end to end, while the armature shaft of the motor is connected directly to the impeller —19— for driving the same.

45 The motor —5— and hub —21— of the blower are located at opposite ends of the impeller —19—, the outer ends of the hub and motor case being journaled co-axially upon suitable bearings —24— on corresponding ends of the housing, said bearings consisting, in this instance, of screws, which are adjustable to take up wear and are held in their adjusted positions by set screws —25—, as shown more clearly in Fig. 4.

55 The slot or opening —23— in the front of the housing through which the delivery nozzle —22— projects is of just sufficient width to permit said nozzle to be adjusted vertically without friction with the walls thereof, the length of the slot or opening being 60 sufficient to allow the delivery nozzle to be moved vertically from an angle of approximately 45 degrees below a horizontal to approximately the same angle above said horizontal, thus permitting the nozzle 65 to move through an arc of about 90 de-

grees, the periphery of the blower case being provided with limiting stops —26— and —27— coöperating with a portion of the main body —8— of the housing to limit the movement of the nozzle through such arc.

70

The portion of the blower case surrounding the impeller is enlarged and eccentrically disposed with relation to the axis of the impeller so as to leave a convolute air space around said impeller gradually increasing in 75 radial depth from the front to the rear and around the lower side with the outer edges of the impeller blades traveling in close proximity to the front wall of the case, the delivery nozzle —22— being alined with the 80 impeller and communicating nearly tangentially with the larger end of the air space around the impeller, thus causing the air to be projected outwardly through the nozzle as the impeller is rotated in the direction indicated by arrow —X—.

85

The weight of the nozzle —22— is sufficient to cause it to rock automatically to its lowermost angle or normal position of rest with the stop —26— in engagement with 90 the adjacent portion of the housing, but may be adjusted vertically from this position by hand to different angles and held in such position by a yielding detent consisting, in this instance, of a ball —28— which is 95 spring-pressed against the periphery of the blower case by a coil spring —29— and may be forced to its holding position under yielding pressure by means of a rod or bar —30— extending vertically through the standard 100 —1— and through an opening —31— in the bottom of the housing section —8—, the lower end of said rod being extended into the base —2— and connected to the inner end of a pedal lever —32— which is fulcrumed at —33— to said base and extends outwardly through an opening therein to the exterior thereof where it is provided with a 105 foot piece —34—.

100

110 It is now evident that when the delivery nozzle —22— is adjusted vertically from its normal position to the desired angle, it may be held in such position by simply depressing the pedal —34— which causes the rod —30— to compress the spring —29— and thereby force the detent —28— into engagement with the periphery of the impeller case with sufficient friction to retain it in its adjusted position as long as the pedal —34— is held in its depressed position, the periphery of the impeller case being provided with a series of notches —35— coöperating with the detent —28— to effect a more positive retention of the delivery nozzle in its adjusted position.

115

120 As soon as pressure upon the pedal —34— is relieved, the weight of the nozzle —22— causes it to return to its normal down position where it is always available without adjustment for drying the hands and is only 125

130

adjusted to its extreme up position for drying the face, but may be adjusted to intermediate positions as may suit the convenience of the user.

- 5 The electric heater —6— consists of several turns of coiled resistance wire wound upon a radially ribbed supporting frame —36— having a central shaft or spindle —37— secured by a set screw —38— in the outer end of the hub —21—, as shown more clearly in Fig. 4, the frame —36— being preferably made of cast iron, but is provided with a heavy coating of enamel —39— of insulating material, such as porcelain upon 70 which the heater wire rests to prevent short circuiting.

This heater is, therefore, located wholly within the blower case between the inlet —17— in the housing and delivery nozzle —22— and, therefore, in the path of travel of the air in passing through the blower, the hub —21— being provided with openings —40— therein to allow the passage of air therethrough from the inlet —17— to 75 the heater.

The electric switch —7— is mounted upon the section —10— of the housing and suitably insulated therefrom by insulating blocks —41—, the movable member as —42— of the switch being provided with a stem —43— projecting through an aperture —44— in the rod or bar —30— so as to be operated by said bar as the latter is raised and lowered by the pedal, the switch being 80 normally opened by the depression of the bar and closed as the bar is elevated to hold the delivery nozzle —22— in its adjusted position.

Both the motor and heater derive current 85 from the same source and are, therefore, connected to the same switch —7— which current may be supplied from any available source by an electric conducting cable 45.

The pedal lever —32—, bar —30— and 90 switch member —42— are self-retracting by means of a spring —46— which assures automatic opening of the switch and release of the detent —28— instantly upon relieving the pressure upon the pedal —34—, thereby 95 normally rendering the machine inactive by cutting off the current to the motor and heater.

In operation, if it is desired to dry the hands only, the user depresses the pedal —34— which instantly closes the switch —7— to energize the heater coil and to start the motor, thereby operating the fan or impeller —19— to create a current of air through the heater from the inlet —17— to 100 the outlet —22—, the heated air being projected outwardly through the delivery nozzle into the room and the user simply holds his moistened hands in the current of heated air at the outlet.

105 The operation is substantially the same

for drying the face, except that the delivery nozzle —22— may be rocked upwardly to direct the current of heated air to the face, it being held in this position by the detent —28— as long as the pedal lever —34— is held depressed, but instantly upon the removal of pressure upon the pedal, the weight of the nozzle —22— automatically returns it to its normal down position, and at the same time opens the switch to stop the motor 75 and to cut off the supply of current to the heater.

What we claim is:

1. In a lavatory fixture, the combination with a housing having an air inlet and an opening, a blower, a motor therefor and a heater, all located within the housing, said blower comprising a fan and an inclosing case therefor adjustable about the axis of the fan and provided with an air inlet and 80 a delivery nozzle extending outwardly through said opening in the housing.

2. In a lavatory fixture, the combination with a housing having an air inlet and an opening, a blower and a co-axial motor 90 therefor, both journaled in the housing, the blower comprising a rotary fan and an inclosing case therefor adjustable about said axis and provided with a delivery nozzle extending outwardly through said opening in 95 the housing, and an electric heater within the blower case in the path of travel of the air therethrough.

3. In a lavatory fixture, a blower having an impeller and a case therefor adjustable 100 about the axis of the impeller and provided with a delivery nozzle, and pedal-operated means for holding the blower case in its adjusted position.

4. In a lavatory fixture, a blower having 105 a delivery nozzle adjustable about a horizontal axis to direct the current of air to different heights and weighted to automatically assume a predetermined normal position, and means operable at will for retaining the nozzle in its adjusted position and including a detent and a spring support therefor placed under increased tension by 110 said means.

5. In a lavatory fixture, the combination 115 of a blower having an impeller and a case therefor having an air inlet and a delivery nozzle, said case being adjustable rotarily about the axis of the impeller, means operable at will for holding the case in its adjusted position, an electric heater wholly within the adjustable blower case in the path of travel of the air therethrough, an electric switch in circuit with the heater, and connections between the switch and said means 120 for closing the switch simultaneously with the operation of the holding means.

6. In a lavatory fixture, a blower having an impeller and a case therefor adjustable about the axis of the impeller and provided 125

with an air inlet and a delivery nozzle, 5 pedal-operated means for holding the case in its adjusted position, an electric motor for the impeller co-axial therewith, an electric heater inclosed within the blower case in the path of travel of the air through the blower, an electric switch connected in circuit with the motor and heater, and connections between the switch and said means for 10 closing the switch simultaneously with the operation of the holding means.

7. In a device of the character described, 15 the combination of an upright standard, a housing secured to the top of the standard and extended beyond opposite sides thereof, said housing having an air inlet in or near one end and a vertically elongated opening in its front in the vertical plane of the standard, an electric heater within the same 20 end of the housing as the air inlet, an electric motor within the opposite end of the housing, a rotary fan secured to the motor shaft in the vertical plane of the opening in the front of the housing, and a case inclosing the fan and heater and provided with a nozzle extending outwardly through said opening, said case being provided with an opening for admitting air from the inlet of the housing to the heater.

30 8. In a device of the character described, the combination of a housing having an enlarged central portion and reduced cylindrical ends, the central portion having a vertically elongated opening in its front side, 35 one of the reduced ends having an air inlet, an electric motor within the other reduced end, a case within the housing adjustable rotarily about the axis of the motor relatively to said housing and provided with a discharge nozzle extending outwardly 40 through the vertically elongated opening, a rotary fan secured to the motor shaft within said case, and an electric heater also within the case, said case having an air inlet 45 communicating with the inlet in the housing.

9. In a device of the character described, 50 the combination of a hollow upright standard, a housing supported on the upright end of the standard and provided with an air inlet, the front side of the case being provided with a vertically elongated opening in the vertical plane of the standard, a fan 55 rotating in said plane, an electric motor at one end of the fan for driving the same, an electric heater at the opposite end of the fan, a case inclosing the fan and heater and adjustable vertically about the axis of the fan and provided with a discharge nozzle 60 projecting through the opening in the front of the housing, a pedal supported on the base of the standard, a rod operated by the

pedal and extending vertically through the standard and into the housing, and a yielding stop actuated by said rod for engaging the periphery of the fan case to hold the latter in its adjusted position when the rod is elevated by the pedal.

10. In a device of the character described, 70 the combination of a hollow upright standard, a housing supported on the upper end of the standard and provided with an air inlet, the front side of the case being provided with a vertically elongated opening 75 in the vertical plane of the standard, a fan rotating in said plane, an electric motor at one end of the fan for driving the same, an electric heater at the opposite end of the fan, a case inclosing the fan and heater and 80 adjustable vertically about the axis of the fan and provided with a discharge nozzle projecting through the opening in the front of the housing, a pedal supported on the base of the standard, a rod operated by the 85 pedal and extending vertically through the standard and into the housing, a yielding stop actuated by said rod for engaging the periphery of the fan case to hold the latter in its adjusted position when the rod is ele- 90 vated by the pedal, and a motor-controlling switch operated by said rod.

11. In a device of the character described, 95 the combination of a rotary fan, an electric motor at one end of the fan for operating the same, an electric heater at the opposite end of the fan, and a case extending entirely around the fan and heater to inclose the same and provided with a discharge opening in one side, and an air inlet near the heater, 100 said case being adjustable rotarily about the axis of the fan.

12. In a device of the character described, 105 the combination of a rotary fan, an electric motor at one end of the fan for operating the same, an electric heater at the opposite end of the fan, a case extending entirely around the fan and heater to inclose the same and provided with a discharge opening in one side and an air inlet near the 110 heater, said case being adjustable rotarily about the axis of the fan, an electric switch controlling the motor, a yielding stop for holding the case in its adjusted position, and pedal-operated means for simultaneously operating the switch and case-holding means.

In witness whereof we have hereunto set our hands this 6th day of July, 1915.
